JOSEPH MARTIN, OF LOS ANGELES, CALIFORNIA

VALVE-OPERATING MECHANISM

Application filed November 18, 1929. Serial No. 407,950.

This invention relates particularly to valve control mechanism of the drop valve type. Valves of this type may be conveniently used, for example, in the bottom of laundry tubs or other fluid containers, which in use require frequent draining.

An object of the invention is to provide a valve, and associated valve controlled mechanism, which may be quickly and accurately manipulated by the operator to remove the fluid contents of a tank.

A further object of the invention is to provide latch mechanism for holding the valve in open position.

The invention will be fully understood from the following description, taken in connection with the accompanying drawings, in which—

Fig. 1 is a top plan view of a tank or chamber provided with my control mechanism;

Fig. 2 is a side elevational view taken on the line 2—2 of Fig. 1;

Fig. 3 is a section taken on the line 3—3 of Fig. 1, showing the valve in the open position;

Fig. 4 is a view similar to Fig. 3, but showing the valve in the closed position;

Fig. 5 is an end elevational view showing the position of the control levers when the valve is in open position; and

Fig. 6 is an end elevational view showing the relative positions of the control levers when the valve is in closed position.

In the drawings, the numeral 10 designates a chamber provided with a bottom wall 11, side walls 12, and end walls 13, which together form a compartment for retaining water or other fluid. If desired, one side wall of the chamber may be made removable to afford access to the working parts. In the chamber shown the top is left open, and flanges 10^a are provided for securing it to the bottom of a larger receptacle.

The bottom wall 11 of the chamber 10 is provided with an outlet opening 14, and a drop valve 15 is positioned within the chamber thereover and serves to prevent flow of liquid through the opening when lowered into closed position on the bottom of the chamber. The valve extends transversely of

the chamber 10 and is preferably of a rectangular shape, the longer dimension extending lengthwise of the chamber.

The valve comprises a bar 16; a metallic plate 17, preferably of greater width than the bar 16; and a series of rubber gaskets 18, which are clamped to the plate 17 by means of suitable cleats or bolts. The chamber 10 is provided at each end with angular guide bars 19, mounted in a vertical inclined position and adapted to engage the opposite end corners along one side of the valve, to direct the valve to seating alignment with the outlet 14. In cases where a closed chamber is desired, a top lid may be provided which may be hingedly mounted on the hinge supporting members 20.

Raising and lowering of the valve 15 is effected by turning a rock shaft 21 which extends longitudinally of the chamber 10 and is journaled in the opposite end walls 13, one end extending through a packing gland 21^a. Arms 22 are secured on the shaft 21; the arms being provided at their outer ends with hooks 23, which removably engage loops 24 secured to the top plate 16 of the valve. A control arm, or lever, 25 is fixedly mounted on the end of the shaft 21 which projects through the packing gland 21^a. The lever 25 is provided on one end with a foot plate 26 and is provided at the opposite end with an adjustable counter-weight 27 which serves to yieldingly hold the lever in position to seat the valve.

The lever 25, together with the arms 22, in effect constitute a lever for raising and lowering the valve, the point of fulcrum being the longitudinal axis of the shaft 21. The weight of the valve itself probably would be sufficient to cause it to seat without the use of a counter-weight; however, a counter-weight affords a more positive action. If desired, a spring may be used instead of a counter-weight, to yieldingly hold the lever in position to seat the valve. When seated, the weight of the fluid maintains the valve in that position.

A stop lug 28 is mounted in a boss 29, which is secured to the chamber 10, means

thus being afforded to limit upward movement of the valve 15.

Valve 15 is, in this type of equipment, usually of considerable weight, and it is necessary to use latching means for retaining the valve in the open position. For this purpose I provide a latch-arm 30, pivotally mounted on the spindle 31 which is journaled in an end wall of the chamber 10. The spindle 31 is offset from the axis of the shaft 21, as shown in Figs. 1, 5 and 6. The latch-arm 30 is provided at one end with a control handle 32, and is provided at the other end with an adjustable counter-weight 33. If desired, a spring may be substituted for this counter-weight. A band or collar 34, provided with a radially extending dog or tooth 35, is mounted fixedly on the projecting end of the shaft 21 to move with lever 25. The collar 20 may, if desired, be made as an integral part of the lever 25. The latch-arm 30 is, in turn, provided with an inclined notch of a configuration similar to the tooth 35.

As shown in Fig. 6, the tooth 35 rests on the top surface of the latch-arm 30 at a point immediately overhanging the notch 36. The latch-arm is thus rendered movable by movement of the lever 25, the movement of the lever causing a corresponding movement of the collar 34 and tooth 35. The counter-weight 33 yieldingly holds the latch-arm in position to be moved by the lever.

In the operation of opening the valve, the lever 25 is turned by depressing the foot plate 26 which, in turn, causes shaft 21 to rotate in a counter-clockwise direction. Inasmuch as the latch-arm 30 turns about an axis offset from the axis of shaft 21, it follows that in opening the valve the tooth 35 and the complementary surface 36 will travel along arcs of different radii to a common point of intersection where latching may be effected. At this point the tooth 35 falls into the notch 36 and the valve is held open. To close the valve the handle 32 is depressed to lower the latch-arm 30 until the tooth 35 clears the notch 36, whereupon the shaft 21 is free to turn under the action of the counter-weight to lower the valve into closed position.

While it is preferred to effect latching by using a tooth and notch of the form shown, it will be obvious that the collar 34 and the latch-arm 30 could be provided with numerous forms of complementary surfaces adapted to releasably engage each other to hold the valve open. Such variations are to be viewed as fully within the scope of the invention.

The foregoing detailed description has been given for clearness of understanding only, and no unnecessary limitations should be understood therefrom, but the appended claims should be construed as broadly as permissible in view of the prior art.

Having described my invention, I claim:

1. In combination: a gravity seated valve;

a seat for the valve; a pivotally mounted lever for raising the valve; means operatively connecting said valve and lever; a latch-arm pivotally mounted to turn about an axis offset from the axis of the lever pivot; and a member movable with the lever complementary to a portion of the latch-arm adapted to releasably engage said portion, when the lever is moved to open the valve, to hold the valve open.

2. In combination: a valve; a seat for the valve, a pivotally mounted lever for raising the valve; means operatively connecting said valve and lever; means for yieldingly holding the lever in position to seat the valve; a latch-arm pivotally mounted to turn about an axis offset from the axis of the lever pivot; and a member movable with the lever complementary to a portion of the latch-arm adapted to releasably engage said portion, when the lever is moved to open the valve, to hold the valve open.

3. In combination: a gravity seated valve; a seat for the valve; a pivotally mounted lever for raising the valve; means operatively connecting said valve and lever; a latch-arm pivotally mounted to turn about an axis offset from the axis of the lever pivot, said latch-arm being movable by movement of the lever; and a member movable with the lever complementary to a portion of the latch-arm adapted to releasably engage said portion, when the lever is moved to open the valve, to hold the valve open.

4. In combination: a gravity seated valve; a seat for the valve; a pivotally mounted lever for raising the valve; means operatively connecting said valve and lever; a latch-arm pivotally mounted to turn about an axis offset from the axis of the lever pivot; means for yieldingly holding the latch arm in position to be moved by the lever; and a member movable with the lever complementary to a portion of the latch-arm adapted to releasably engage said portion, when the lever is moved to open the valve, to hold the valve open.

5. In combination: a gravity seated valve; a seat for the valve; a pivotally mounted lever for raising the valve; means operatively connecting said valve and lever; a latch-arm pivotally mounted to turn about an axis offset from the axis of the lever pivot; and a member movable with the lever complementary to a portion of the latch-arm adapted to releasably engage said portion, when the lever is moved to open the valve, to hold the valve open, said members adapted to be engaged, by movement of the latch arm, to permit closing of the valve.

6. Valve mechanism comprising, in combination: a valve; a seat for the valve; a shaft provided with an arm for raising and lowering the valve; a lever for turning said

shaft; means for yieldingly holding the lever in position to seat the valve; a tooth extending from said shaft and mounted to turn with said lever; a latch-arm pivotally mounted to turn about an axis offset from the axis of said shaft, said latch-arm being provided with a notch adapted to engage said tooth to hold the valve open; and means for yieldingly holding the latch-arm in position to be moved by said lever.

10 7. In a device of the character set forth: a chamber having an outlet in its bottom; a valve for closing said outlet; a shaft journaled in the walls of said chamber and provided with an arm for raising and lowering said valve; a lever mounted on said shaft, said lever being operable to turn the shaft to raise and lower the valve; a tooth extending from said shaft and mounted to turn with said lever; and a latch-arm pivotally mounted to turn about an axis offset from the axis of said shaft, said latch-arm being provided with a notch adapted to engage said tooth to hold the valve open.

15 8. In a device of the character set forth: a chamber having an outlet in its bottom; a valve for closing said outlet; a shaft journaled in the walls of said chamber and provided with an arm for raising and lowering said valve; a lever mounted on said shaft, said lever being operable to turn the shaft to raise and lower the valve; means for yieldingly holding the lever in position to close said outlet; a tooth extending from said shaft and mounted to turn with said lever; and a latch-arm pivotally mounted to turn about an axis offset from the axis of said shaft, said latch-arm being provided with a notch adapted to engage said tooth to hold the valve open.

20 9. In a device of the character set forth: a chamber having an outlet in its bottom; a valve for closing said outlet; a shaft journaled in the walls of said chamber and provided with an arm for raising and lowering said valve; a lever mounted on said shaft, said lever being operable to turn the shaft to raise and lower the valve; a tooth extending from said shaft and mounted to turn with said lever; a latch-arm pivotally mounted to turn about an axis offset from the axis of said shaft, said latch-arm being provided with a notch adapted to engage said tooth to hold the valve open; and means for yieldingly holding the latch arm in position to be moved by said lever.

25 In witness that I claim the foregoing I have hereunto subscribed my name this 10th day of October, 1929.

30 JOSEPH MARTIN.

CERTIFICATE OF CORRECTION.

Patent No. 1,775,908.

Granted September 16, 1930, to

JOSEPH MARTIN.

It is hereby certified that error appears in the printed specification of the above numbered patent requiring correction as follows: Page 2, line 125, claim 5, for the word "engaged" read disengaged; and that the said Letters Patent should be read with this correction therein that the same may conform to the record of the case in the Patent Office.

Signed and sealed this 21st day of October, A. D. 1930.
